WATERPROOF ANTENNA CONNECTOR

Elvie Bauer, 9100 Long Lane, Cincinnati, Ohio

Filed Sept. 14, 1962, Ser. No. 71,697

Term of patent 14 years

(Cl. D26—1)

Fig. 1

Fig. 3

Fig. 2

Fig. 4

Fig. 5

FIGURE 1 is a top plan view of a waterproof antenna connector embodying my new design; and

FIGURE 2 is a front elevational view of a waterproof antenna connector embodying my new design; and

FIGURE 3 is a cross-sectional view thereof taken on lines 3—3 of FIGURE 2; and

FIGURE 4 is a side elevational view thereof; and

FIGURE 5 is a bottom plan view of the waterproof antenna connector embodying my new design.

I claim:

The ornamental design for a waterproof antenna connector, as shown.
